Edmund St. of Lowell Mass
Assignor to
Lowell Manf Company
Letters Patent No 1355, Dated Dec 18th 1860

Fall whom it may concern:

Be it Known that I Edmund St.

of Lowell, in the County of Middlesex and State of Massachusetts, have originated and designed a new Pattern for Carpets or other Fabrics, of which the following is a full, clear, and exact description, reference being had to the accompanying drawings, making part of this specification.

In the corner A, is a quarter of a four pointed figure resting in the block B. said block is surrounded by the frame 1, and scalloped band 2. Radiating from the band 2, are sprigs 3, surrounded by small balls. The broad band C, also surrounds the sprigs 3, and is itself surrounded by sprigs D, at the side is a small group of leaves and flowers resting on the ground E, said ground is enclosed by the broad frame F, which slightly overlaps the scalloped band C. In the corner is a quarter of a square figure resting on the scroll figure H. Between the scroll fig H, and the frame 1, is a group of leaves and flowers. The colors employed for the different portions of this design, may be varied to suit the taste and wish of the manufacturer.

Claim

What I claim as my invention and desire to secure by Letters Patent, is:-
